UNITED STATES PATENT OFFICE.

FRANKLIN J. KLEPPER, OF EARLING, IOWA.

GARTER.

Application filed June 23, 1924. Serial No. 721,924.

To all whom it may concern:

Be it known that I, FRANKLIN J. KLEPPER, a citizen of the United States, residing at Earling, in the county of Shelby and State of Iowa, have invented certain new and useful Improvements in Garters, of which the following is a specification.

This invention appertains to garment supporters and more particularly to an improved type of stocking supporter.

The primary object of the present invention is to provide novel means associated with the body of a garter for gripping the stocking, whereby accidental release of the stocking is prevented, the fastener being so constructed as to compensate for the thickness of the garment being supported, thereby permitting relatively heavy stockings to be held as effectively as relatively thin stockings.

A still further object of the invention is to provide a garter embodying a novel stocking engaging member including resilient arms for firmly holding the stocking about the stud of said member, the arms being adapted for movement toward and away from each other to compensate for different thicknesses of the garment being supported.

A still further object of the invention is to provide an improved garter of the above character, which will be durable and efficient in use, one that will be simple and easy to manufacture and one which can be placed upon the market at a small cost.

With these and other objects in view, the invention consists in the novel construction, arrangement and formation of parts, as will be hereinafter more specifically described, claimed, and illustrated in the accompanying drawings, in which drawings,

Figure 1 is a perspective view of the garter.

Figure 2 is a detail elevation of one of the novel stocking engaging elements, a portion of the stocking engaging element being broken away, the element being of a slightly modified form from that shown in Figure 1.

Referring to the drawings in detail, wherein similar reference characters designate corresponding parts throughout the several views the letter A indicates a garter and B the novel stocking engaging elements carried thereby. The garter A can be of any desired character or form and it is to be understood that the same can be simply shown to illustrate the use of the improved

stocking engaging element B. As shown the garter A comprises an annular limb engaging band 5 having a body 6 formed thereon or connected therewith, and the ends 60 of the body support the depending tabs 7 which form a part of the novel stocking element B.

Each stocking engaging element B has formed transversely across the tabs 7 adjacent to the upper end thereof with a sleeve or hinge barrel 8 for a purpose, which will be hereinafter more fully described. A headed stud 9 is carried by the tab 7 adjacent to its lower end and the stocking to be supported 65 is adapted to be placed over this stud in the manner common with ordinary stocking supporters. In accordance with this invention oppositely bowed arcuate resilient arms 10 and 11 are provided and these arms are connected at their upper ends to the terminals 70 of a connecting bight portion 12 which is rotatably mounted within the sleeve or barrel 8. The lower ends of the arcuately bowed arms 10 and 11 are provided with 75 substantially semi-circular jaws or grips 13 for engaging about the shank of the stud 9 and the outer terminals of these grips are provided with outwardly extending finger pieces 14 which rests upon the said arms 10 and 11 and are thus held away from the 80 stocking or the like so as not to injure the same. It will be readily seen that should the finger pieces be permitted to engage the stocking or the like, they would be very apt 85 to tear the same.

In Figure 2 a slightly modified form of the invention is shown in which the arcuate grips 13 extend a slightly greater distance than half way around the shank of the stud 9 so that the outer or free terminals of the grip will lie in overlapping relation relative to one another. The outer terminals of the grips are then provided with relatively short 95 outwardly extending arcuate finger gripping portions 15.

In use of the improved stocking engaging element the stocking to be supported is placed over the headed stud 9 after which the bowed arms 10 and 11 are swung down 105 toward the stud and the finger grips are grasped by the operator and pulled in opposite directions so as to flex the arms 10 and 11 and to permit the grips 13 to extend about the shank of the stud outwardly of 110 the head, after which the finger pieces are released and the grips 13 will firmly hold

the stocking in intimate contact with the stud by the inherent resiliency thereof. Now it is obvious that if the stocking is formed of relatively heavy material that the grips ⁵ can flex laterally so as to compensate for the thickness thereof.

Changes as to detail may be made without departing from the spirit or the scope of this invention, but:—

10 What I claim as new is:—

A garment supporter comprising a tab, a

stud carried by the tab, a pair of resilient arms also carried by the tab, each being bowed longitudinally and having their curves arranged in opposed relation, said arms being provided with grips arranged to engage said stud, the outer terminals of the grips being provided with diverging finger pieces resting upon the opposite arms. ¹⁵

In testimony whereof I affix my signature.

FRANKLIN J. KLEPPER.
